S. King,
Making Staves,
Patented Aug. 29, 1833.

773d

Aug. 24, 1833

James M. King of Chittenango, New York,

Letter Patent.

The schedule referred to in this Letter Patent and making part of the same containing a description in the words of the said James M. King himself of his improvement in the law for sawing staves and other cylindrical work,

To all, to whom these presents shall come, greeting: Be it known that I, James M. King of Chittenango in the County of Madison and State of New York, have invented a new and useful improvement in a law for sawing staves & other cylindrical work, and the following is a full and exact description of the construction and operation of the said law as invented or improved by me:

The law to be in a cylindrical form the surface of the law to be concave, convex, or flat, for the purpose of forming the bilge, or swell in the stave, or for giving a longitudinal curve to the work, or sawing it straight as the case may require, the law to be supported and set of friction rollers or wheels, which are to be supported in the following manner: Two cylinders or rims made of cast iron or wood to be fastened by bars or cross pieces and at sufficient distance apart to admit the said friction rollers or wheels to play between them, the bars to run through and within the said rim and two of them to extend so far as to fasten the law frame to any permanent part of the building or the frame upon which the whole machine rests. The cylinder or rim to have holes through them perpendicular to the surface to receive pins, or standards to pass through them, which are to have each a head or knot of metal or composition formed or mounted upon said pins, or standards, with holes in them to receive the

grippers of the said friction roller, and upon which the said friction rollers rest, and move, The said posts or standards to have a screw head cut upon them, when they pass thro the said cylinders or arms with two nuts on each for the purpose of supporting, raising or lowering the posts and setting the roller to the saw, or to have longitudinal holes in the edge of the cylinders for the purpose, and receiving bolts to run thro them, by which the posts or standards may be made fast by a nut or screw, or raised or lowered at pleasure, The said friction rollers may also run upon pivots, One of the said rollers, or one or more of them to be set askew or making a small angle with the other rollers at the end toward the teeth of the saw, to incline the saw back against wheels which are fixed on axles for the purpose of preventing the saw from running off from the rollers, the axis of the last-mentioned wheels to be fastened on the back cylinder with a screw in such manner as that they may be moved back and forward at pleasure, The saw being fixed upon the rollers a band or strap passes round it as round a drum except a sufficient space to admit the timber that is to be sawed to pass thro the two sides of the band, Friction rollers are placed one above and one below the carriage that carry the timber to be sawed, to keep the band close to the saw, The top roller to be fastened by arms fastened to the cylinder, the other to the frame below, The timber to be sawed to be carried between the sides of the band where they leave the saw, on a carriage, The band passing round the saw also, passes over a drum separate from the machine and propelled by any power, all the above-mentioned wheels or rollers to be made of wood or metal or any kind of composition, It will require about ten friction rollers to support a saw two feet in diameter, which is the proper size for a barrel, and for other uses in proportion, What I

170732X
claim as my invention in the above described machine is
the occurring of the saw upon the friction rollers without
being attached to any block or cylinder, and also its
peculiar quality of sawing staves and other work in low
optical curves.

For further illustration of the same I refer to
the model and drawing of the same deposited in the
Patent Office.

In testimony whereof, I have hereunto
subscribed my name at the Village of Chittenango, this
twentieth day of August 1833.
